(57) **CLAIM**

The ornamental design for a fluid container, as shown and described.

DESCRIPTION

FIG. 1 is a front, top, and side perspective view of a fluid container showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, top, and side perspective view thereof, with the lid shown in an open position;

FIG. 9 is a front, top, and side perspective exploded view thereof, with the lid shown in an open position;

FIG. 10 is a front view thereof, with the lid shown in an open position;

FIG. 11 is a back view thereof, with the lid shown in an open position;

FIG. 12 is a left side view thereof, with the lid shown in an open position;

FIG. 13 is a right side view thereof, with the lid shown in an open position;

FIG. 14 is a top view thereof, with the lid shown in an open position; and,

FIG. 15 is a bottom view thereof, with the lid shown in an open position.

The broken lines in the drawings depict portions of the fluid container that form no part of the claimed design.

1 Claim, 13 Drawing Sheets
